UNITED STATES PATENT OFFICE.

HUGH JUDGE, OF JOHNSTOWN, NEW YORK.

KNOCKDOWN STAND OR TABLE.

1,026,748.

Specification of Letters Patent.

Patented May 21, 1912.

Application filed October 19, 1910. Serial No. 587,992.

To all whom it may concern:

Be it known that I, HUGH JUDGE, a citizen of the United States, residing at Johnstown, county of Fulton, and State of New York, have invented certain new and useful improvements in Knockdown Stands or Tables, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a top plan view of a knock-down table made in accordance with my invention, with a portion of the top broken away. Fig. 2 is a plan view of one of the horizontal braces for the top. Fig. 3 is a plan view similar to Fig. 1 partly broken away, and with the table top removed and showing a curved form of horizontal brace employed with a circular top for the table. Fig. 4 is a vertical section taken on the broken line 4—4 in Fig. 1. Fig. 5 is a side view of one of the cross-pieces for the table top or bottom. Fig. 6 is a similar view of the companion cross-piece therefor. Fig. 7 is a horizontal cross-section taken on the broken line 7—7 in Fig. 4, showing the four-way aperture through the center post. Fig. 8 is a vertical cross-section taken on the broken line 8—8 in Fig. 4, showing the groove and tenon connection between the end of a diagonal brace and the neighboring end of one of the cross-bars for the top or bottom. Fig. 9 is a view in end elevation of a removable foot-block detached. Figs. 10 and 11 are side views of the tenoned and grooved neighboring ends of a pair of diagonal braces. Fig. 12 is a side view of one of the wedges.

The principal object of the invention is to provide a table made up of members which can be readily taken apart or assembled without the use of nails or screws.

Other objects will appear in connection with the following description.

Referring to the drawings wherein the invention is shown in preferred form the post, 1, has a four-way aperture, 2, near each end. Through each of these apertures are inserted

two cross-bars, 3, notched at, 4, to fit together, and each of said cross-bars being notched at, 5, to receive the body of the post, said bars extending at right angles to one another in a horizontal plane through the respective four-way apertures 2. Each pair of said cross-bars is tightly held in place within the four-way aperture by means of a wedge, 7, which is driven tightly in between the lower cross-bar and the bottom wall of the four-way aperture. The depth of the notches, 5, in the upper cross-bars corresponds with the thickness of the upper outer end-wall, 6, of the post, so that when the parts are thus wedged together, the top surfaces of the cross-bars at the top of the post will be substantially flush with the upper end of the post. A diagonal brace, 8, extends from the outer end of each cross-bar, 3, to an intermediate point on the post, 1, said braces being stepped into the respective cross-bars at, 9, and each having a tenon, 10, fitting a mortise or groove in the cross-bar to prevent sidewise movement. The inner end of each of the upper braces, 8, is formed with a notch, 11, to receive a tenon, 12, on the neighboring end of the corresponding lower brace, which tenon, 12, enters an opening, 13, in the side of the post, whereby the two braces bear against each other and against the post, and are both prevented from lateral displacement relatively to each other and to the post.

When the parts are assembled as shown and described, and the wedges, 7, driven home, the parts will be securely held together without the use of nails or screws, but can be easily separated by simply driving out the wedges.

Each end of the lower cross-bars is shown provided with a foot, 14, the sides of the cross-bar being provided with bayonet grooves, 15, adapted to receive the respective lugs, 16, on the side-arms of the foot. The foot is applied from below the bottom cross-bar, 3, the lugs, 16, traveling upward and then outward along the bayonet grooves, 15, until they reach the outer ends of said grooves, in which position the foot is retained by the neighboring lower brace, 8, 10, which is of a width sufficient to overlap laterally the arms of the foot. It will be understood that the foot is placed in position before the lower brace, 8, is applied to the lower cross-bar, 3.

Horizontal braces, 17, may be inserted between the neighboring ends of cross-bars, 3,

at the top of the table, said braces having tenons, 18, adapted to enter corresponding openings, 19, in the side of the upper cross-bars, said openings being in the form of 5 longitudinal grooves open at their outer ends to permit the braces to be slid into place.

As shown in Figs. 1 and 2, the horizontal braces are in the form of straight braces 10 adapted for forming the sides of a substantially rectangular table-top which can be completed by applying thereto a continuous band, 22, extending entirely around the top of the table embracing the ends of 15 the top cross-bars, 3, as well as the horizontal braces 17 and serving to prevent the outward escape of said braces. The horizontal braces, 17, are preferably rabbeted at, 23, and the ends of the top cross-bars similarly rabbeted at, 24, to receive the band 22.

Boards, 20, may be employed to finish the table top, said boards being rabbeted to fit within the band, 22, as shown at, 25, and being tongue-and-grooved together as shown 25 in Fig. 4. If a circular table top be desired curved horizontal members, 17^a, may be employed with a circular band, 22^a, as shown in Fig. 3.

The stand or table thus constructed can 30 be easily put together without the use of special tools or nails or screws, and can be readily taken apart and the parts compactly assembled for storage or transportation.

When the parts are assembled as above 35 described, and the wedges, 7, driven tightly into place, a rigid substantial stand or table is produced capable of supporting great weight.

What I claim as new and desire to secure 40 by Letters Patent is—

1. In a stand or table, and in combination, a central post having a closed end; and provided near said end with an aperture through the post, and provided with side- 45 openings in the vertical plane of said aperture; a horizontal cross-bar removably inserted through said aperture; detachable diagonal braces stepped at one end into the respective ends of said cross-bar, and at the 50 other end adapted to occupy the respective side-openings in said post; and a removable locking-key interposed between the wall of said aperture and the outer side of said cross-bar.

2. In a stand or table, and in combination, a central post having a closed end, and provided near said end with a four-way aperture, and provided with side-openings; a pair of horizontal cross-bars removably inserted one above the other at right angles 55 to each other through said four-way aper-

ture; detachable diagonal braces stepped at one end into the respective ends of said cross-bars, and at the other end adapted to occupy the respective side-openings in said post; and a removable locking-key interposed between the wall of said aperture and the outer of said cross-bars. 65

3. In a stand or table, and in combination, a central post having closed ends, and provided near each end with an aperture through the post, and provided with side-openings in the vertical plane of said aperture; a pair of horizontal cross-bars inserted in parallel relation to each other through 75 said respective apertures; a removable locking-key interposed between the wall of one of said apertures and the inner side of the cross-bar extending therethrough; a pair of braces stepped at their outer ends into the 80 respective ends of said cross-bar, and extending diagonally inward toward the post; another pair of braces stepped into the respective ends of said other cross-bar, and extending diagonally inward to said post, 85 and having on their inner ends members adapted to occupy the respective side-openings in the post, and members adapted to engage the inner ends of the respective first-mentioned diagonal braces; and a removable locking-key interposed between the outer side of said other cross-bar and the wall of the aperture through which the same passes. 90

4. In a stand or table, and in combination, 95 a central post; a cross-bar extending horizontally through an aperture in the lower end of said post and provided near its ends with a bayonet groove; a foot having side-arms provided with a projection adapted to 100 travel along said bayonet groove; and a removable brace stepped into the outer end of said cross-bar in engagement with said foot and serving to hold said foot at the end of said bayonet groove and extending 105 upward and inward to said post.

5. In a stand or table, and in combination, a central post; horizontal cross-bars provided with longitudinal side-grooves open at their outer ends; horizontal braces formed 110 with tenons adapted to be slid into said grooves through their open ends; and a band inclosing said cross-bars and horizontal braces, and serving to retain said braces within said grooves. 115

In testimony whereof, I have hereunto set my hand this 11th day of October, 1910.

HUGH JUDGE.
